PATENTED
DEC 24 1867

United States Patent Office.

MILO R. SNODGRASS, OF JAMESTOWN, OHIO.

Letters Patent No. 72,556, dated December 24, 1867.

IMPROVEMENT IN SEED-PLANTER AND CULTIVATOR.

The Schedule referred to in these Letters Patent and making part of the same.

TO ALL WHOM IT MAY CONCERN:

Be it known that I, MILO R. SNODGRASS, of Jamestown, in the county of Greene, and State of Ohio, have invented a new and improved Seed-Planter and Cultivator; and I do hereby declare that the following is a full, clear, and exact description thereof, which will enable those skilled in the art to make and use the same, reference being had to the accompanying drawings, forming part of this specification.

This invention relates to a new and improved seed-planter and cultivator combined; and it consists in a peculiar construction and arrangement of the several parts, as hereinafter fully shown and described, whereby the machine may be made to work in either of the above-named capacities, in a perfect manner. In the accompanying sheet of drawings—

Figure 1 is a plan or top view of my invention complete, or with all the parts attached.

Figure 2, a plan or top view of the same, with the ploughs removed.

Figure 3, a rear view of the same, partly in section.

Figure 4, an inverted plan of the seed-boxes, and bottom plate connected therewith.

Similar letters of reference indicate corresponding parts.

A represents a rectangular horizontal frame, which is mounted on the wheels B B, and provided with the usual draught-pole, C. D D represent two seed-boxes, which are secured, one to each side of the rear part of the frame A, and have a bottom plate, E, attached, said plate extending entirely across the machine, or from seed-box to seed-box, as shown clearly in fig. 3. This plate E has two holes, a a, made through it, underneath each hopper, and on this plate there is fitted a slide, F, which has a reciprocating motion given it through the medium of a hand-lever, G, the ends of the slide F extending through the seed-boxes, and having two holes, b b, made through it, near each end (see figs. 2 and 3.) The upper surface of the slide, a certain distance from each end, is grooved longitudinally, as shown at c. These grooves are designed to catch dirt, chaff, &c., forming chambers for the same, and preventing it from interfering with the proper distribution of the seed. In the lower part of each seed-box, over the slide F, there is fitted a slotted plate, H, having a chamber, d, at each end, in which cut-off brushes e are placed, (see fig. 3.) By this arrangement the seed is cut off, or the holes b b covered, and effectually separated from the seed in the seed-boxes, when either hole b comes in line with a hole, a, in plate E. To the under side of plate E, directly underneath each seed-box, there is secured a discharge-spout, I. In each of these spouts there is fitted a valve, J. These valves are hung on axes or pivots, f, and to one end of each axis a lever, K, is attached, the upper ends of which pass up through oblong slots, g, in plate E, and are connected to the slide F. By means of this connection the valves J are moved by the slide F, and said valves are designed to be closed and retain the seed in the spouts I, as it is discharged from the seed-boxes, the valves opening and discharging the seed from the bottom of the spouts into the ground where there is no discharge from the seed-boxes into the spouts. By this arrangement the seed is discharged quite close to the ground, and without being scattered, and in the exact place desired, the lower end of the spouts I having covering-sleeves h attached, which are shown in fig. 3. The furrows to receive the seed are made by shares, L, at the lower ends of standards M, which are attached to beams N N, the front ends of the latter being secured to the front cross-bar of frame A by hinges or joints i. Each beam, N N, near its rear end, is connected by bars, O O, to cranks j j, at the ends of a shaft, P, which has its bearings in the upper ends of uprights Q Q, on the main frame A, and has a lever, R, extending backward from it, within convenient reach of the driver on seat S. By actuating this lever, the driver may raise the ploughs out of the ground, when required, and by securing said lever in a position with its rear end elevated, the ploughs may be retained in the earth, the ploughs being held up above the ground when the outer end of the lever is secured in a depressed position. The lever is secured in either of the two positions described, by having catches or projections, k k, attached to an upright, T, on the frame A.

In order to convert the machine into a cultivator, I connect two plough-beams, M' M', at their front ends, by a semicircular bar, N', which is pivoted to the front cross-bar of frame A, as shown at l. These beams are supported, near their rear ends, by a chain, m, from the shaft P, the central part of which is curved or bent, to operate as a crank, and admit of the ploughs N' of said beams being raised and lowered through the medium of lever R, precisely like the shares L. The beams M' M' are moved laterally by means of the pendent rods u u, which extend down from a treadle, U, pivoted centrally to a cross-bar, W, attached to the frame A. The

treadle is actuated by the feet of the driver, the rods *u u* being carried down between the beams *M' M'*, as shown in fig. 1. The axles *V V*, of the wheels *B B*, are arranged in the frame *A* so as to be movable, and admit of being adjusted further into or out from the frame *A*, so that the wheels *B B* may be placed at a greater or less distance apart, as occasion may require.

I claim as new, and desire to secure by Letters Patent—

1. The grooves *e*, in the upper surface of the slide *F*, in combination with the holes *b* in said slide, and the holes *a* in the plate *E*, all arranged substantially as and for the purpose set forth.
2. The chambers *d*, on the plates *H*, to receive the cut-off brushes *e*, in combination with the holes *b* in slide *F*, and the holes *a* in plate *E*, for the purpose specified.
3. The valves *J*, in the spouts *I*, when operated from the slide *F*, substantially in the manner as and for the purpose set forth.
4. The adjustable beams *M'*, arranged so as to be operated through the medium of the crank-shaft *P* and lever *R*, when said parts are used in connection with the upright *T*, provided with catches or projections *k k*, all arranged substantially as and for the purpose specified.
5. The adjustable beams *M' M'*, applied to the frame *A*, and operated through the medium of the treadle *U* and pendent rods *u u*, all arranged substantially as and for the purpose specified.
6. The adjustable axles *V V*, of the wheels *B B*, arranged substantially as and for the purpose set forth.

MILO R. SNODGRASS.
